CLAIM

The ornamental design for a grommet, as shown and described.

DESCRIPTION

Embodiment 1

FIG. 1 is a left, front, and top perspective view of grommet, FIG. 2 is a right, rear, and bottom perspective view thereof, FIG. 3 is a front elevational view thereof, FIG. 4 is a rear elevational view thereof, FIG. 5 is a left side elevational view thereof, FIG. 6 is a right side elevational view thereof, FIG. 7 is a top plan view thereof, FIG. 8 is a bottom plan view thereof, FIG. 9 is a 9-9 line sectional view thereof, FIG. 10 is a 10-10 portion enlarged view thereof, FIG. 11 is an end view taken along line 11-11 thereof, FIG. 12 is a 12-12 line sectional view thereof, FIG. 13 is an enlarged central longitudinal sectional view of a 10-10 portion thereof, FIG. 14 is a left, front, and top perspective view thereof in the state that the umbrella portion is opened, FIG. 15 is a right, rear, and bottom perspective view thereof in the state that the umbrella portion is opened, FIG. 16 is a front elevational view thereof in the state that the umbrella portion is opened, FIG. 17 is a rear elevational view thereof in the state that the umbrella portion is opened, FIG. 18 is a left side elevational view thereof in the state that the umbrella portion is opened, FIG. 19 is a right side elevational view thereof in the state that the umbrella portion is opened, FIG. 20 is a top plan view thereof in the state that the umbrella portion is opened, FIG. 21 is a bottom plan view thereof in the state that the umbrella portion is opened, FIG. 22 is a 22-22 line sectional view thereof in the state that the umbrella portion is opened, FIG. 23 is a 23-23 portion enlarged view thereof in the state that the umbrella portion is opened, FIG. 24 is a 24-24 line sectional view thereof in the state that the umbrella portion is opened,

(Continued)

FIG. 25 is a 25-25 line sectional view thereof in the state that the umbrella portion is opened, and,
 FIG. 26 is an enlarged central longitudinal sectional view of a 23-23 portion thereof in the state that the umbrella portion is opened.
Embodiment 2
 FIG. 27 is a left, front, and top perspective view thereof,
 FIG. 28 is a right, rear, and bottom perspective view thereof,
 FIG. 29 is a front elevational view thereof,
 FIG. 30 is a rear elevational view thereof,
 FIG. 31 is a left side elevational view thereof,
 FIG. 32 is a right side elevational view thereof,
 FIG. 33 is a top plan view thereof,
 FIG. 34 is a bottom plan view thereof,
 FIG. 35 is a 35-35 line sectional view thereof,
 FIG. 36 is a 36-36 portion enlarged view thereof,
 FIG. 37 is an end view taken along line 37-37 thereof,
 FIG. 38 is a 38-38 line sectional view thereof; and,
 FIG. 39 is an enlarged central longitudinal sectional view of a 36-36 portion thereof.
 The broken lines shown in the drawings illustrate portions of the grommet that form no part of the claimed design.
